UNITED STATES PATENT OFFICE.

JAMES CLAYTON, OF COVENTRY, ENGLAND, ASSIGNOR TO THE VISCOSA COMPANY, OF MARCUS HOOK, PENNSYLVANIA, A CORPORATION OF PENNSYLVANIA.

MOTOR-DRIVEN APPARATUS.

Application filed August 26, 1919. Serial No. 320,019.

To all whom it may concern:

Be it known that I, JAMES CLAYTON, a subject of the King of Great Britain, residing at 12 Middlesborough Road, Coventry, 5 in the county of Warwick, England, have invented new and useful Improvements in Motor-Driven Apparatus, of which the following is a specification.

My invention relates to apparatus employed in the manufacture of artificial silk, according to what is known as the Topham system, wherein viscose, or the like, is ejected from a nozzle into a setting bath and the threads formed are led under and over suitable 15 guiding devices and down through a thread-guide, or funnel into a rapidly rotating spinning-box in which the thread is coiled and the object of my invention is to overcome certain objections incidental to 20 such apparatus as hitherto constructed.

In such apparatus I have found that the best results cannot be obtained unless, during the operation of the apparatus, proper alignment be maintained between the axes of 25 the spinning-boxes and their spindles and the thread-guides, or funnels, through which the threads pass before they enter the spinning-boxes.

This maintenance of alignment is not satisfactorily attained by supporting the spinning boxes and their adjuncts in the manner hitherto practised and it is one of the 30 objects of my present invention to provide means which will effect and maintain such alignment and allow the spinning-boxes to be adjusted with facility and maintained in true position.

The spinning-boxes, as hitherto made, are perforated around their periphery and there 35 is a large hole in the top, or cover, of the spinning-box for the passage of the thread-guide, or funnel, this hole being made large to avoid contact of this part of the box with the said thread-guide, or funnel, owing to 40 deviation of the box from alignment with the said guide, or funnel, and also to allow the attendant to see a coloured disc at the centre of the bottom of the interior of the spinning-box, by which disc he adjusts the 45 funnel to the axis of rotation of the spinning-box.

I have found that the circulation of large volumes of air, (due to centrifugal action) through the spinning-boxes and the space

surrounding them and through the thread 55 (laden with chemicals) coiled in the said boxes, whilst they are in operation, is detrimental and results in the formation of large quantities of corrosive vapours, or gases, which are injurious to the apparatus and injurious to health and another object of my 60 invention is to overcome this objection.

Further, when the spinning-boxes are driven by electric motors mounted on the spindles of the said boxes, it is an advantage 65 to maintain the motors as near normal temperature as possible and it is a further object of my invention to effect this.

According to my invention true alignment 70 of the spinning-boxes, and their spindles and motors, with the thread-guides, or funnels, is practically effected by flexibly mounting the motor-casings (or some equivalent part in connection with the spinning-box spindles) on three, or more, adjustable 75 resilient supports (which I will refer to as spring supports) so that the openings in the top of the spinning-boxes, through which openings the thread-guides, or funnels, pass, can be made so small, or fit around the sides 80 of the thread-guides, or funnels, so closely, as to prevent the circulation of the aforesaid large volumes of air through the spinning-boxes and the space surrounding them, and therefore overcome the objections consequent thereon and I, by this means, so utilize the exhausting effect due to the rotation of the perforated spinning-boxes as to 85 maintain, during the operation of the machine, a partial vacuum in the said boxes 90 which obviates, or greatly lessens, the formation of injurious vapours, or gases, from the chemicals carried over into the boxes by the threads, and allows such chemicals to pass away as liquid for re-use if desired. 95

I also provide means by which air is caused to pass in contact with the electric motors carried by the spindles of the spinning-boxes, so that the said motors are prevented from becoming overheated and are 100 thereby rendered more efficient and durable.

I will describe, with reference to the accompanying drawings, how my invention may be performed, premising that I do not limit myself to the precise details illustrated 105 and hereinafter described with reference thereto.

Figure 1 is a transverse section of one side

of so much of a machine as is necessary to illustrate the application of my invention thereto.

Figure 2 is a vertical section of a rail and 5 one of the motor-casings, and means whereby its flexible mounting for proper alignment and regulation and fixing in proper position, are effected. Figure 3 is a vertical section across the rail between two spinning-boxes shewing the motor-casing in elevation, and Figure 4 is a plan. These figures also shew the passages for air to prevent overheating of the motors.

Figure 5 is a vertical section shewing the 15 arrangement of the passages for air, modified for application to the rail which is moved up and down when the machine to which my invention is applied is one in which the spinning-boxes are reciprocated 20 as well as rotated.

Figures 1 and 5 are drawn to a smaller scale than that to which Figures 2, 3 and 4 are drawn.

Each spinning-box 1 is perforated around 25 its periphery as indicated, for example, at 1^a, and is mounted, as usual, on a spindle 2, which carries the rotor 3^a of an electric motor 3, (not indicated in Figure 3) the stator 3^b of which is carried by the casing 4, 30 which encloses the motor and has bearings 4^a and 4^b, at top and bottom, in which bearings the spindle 2, rotates against ball-bearings 5 above, the bottom-end of the spindle 2 being cupped and resting on a ball 6, which 35 bears upon another ball 7, which is received in a cup in the end of the adjusting screw 8, which can be locked in its adjusted position by the lock-nut 9 bearing against the end of the motor-casing stem 10, which passes 40 through an opening in the rail 11, the said end of the stem being screwed and provided with an adjusting lock-nut 12 and spring, or spring-washer 12^a whereby the pressure upon the spring supports can be simultaneously regulated and the vertical position 45 of the motor-casing and other parts be adjusted.

The motor-casing 4, has three feet cast upon it at 13, each of which rests upon an 50 inverted cup 14. The rail 11, carries three corresponding stems 15, which can be adjusted (by a spanner applied to the head 15^a) in screwed holes in the rail 11, and be fixed in the adjusted position by the lock-nuts 15^b. 55 The upper ends of the stems 15, enter the inverted cups 14, which each contain a spring 16.

The top part of the casing 4, is shewn as being secured to the body part of the said 60 casing by screws 13^b.

Each thread-guide, or funnel, 17, preferably consists of a glass, or like, tube open at top and perforated at its lower end, through which the thread, from the godet 65 above, is passed, in the usual way, into the

spinning-box 1, the said tube being enclosed in an outer tube made of acid-proof metal. For bearing against, and reciprocating on, this outer tube the top of each spinning-box is provided with a packing-box 20, 70 which contains any suitable packing 20^a, a suitable packing for this purpose being wood saturated with lubricating oil.

Owing to the closure of the box, or the 75 restriction of its opening, around the thread-guide, or funnel, and to the centrifugal force set up by the high speed of the box there is, when the machine is in operation, always a partial vacuum within the box and the hitherto objectionable formation of vapours, or gases, and the circulation thereof, with the air, through the boxes and the space around them enclosed by the casing, 25, is prevented, or greatly lessened, with the beneficial effects hereinbefore mentioned.

The motors are cooled by air supplied to them, or drawn into their casings, so that 80 a current of air passes between the rotors and stators of the motors. This is shewn in the drawings as being effected by forcing, 90 or drawing, air through the rails 11, which are, at 11^a, made hollow for the purpose the hollow communicating, by passages 11^b, with a channel 11^c, through which passes one of the stems 15, of the aforesaid spring seatings 95 for the motor-casings, this stem being prolonged at 15^c, for the purpose, the prolongation entering a boring 13^c, in a continuation, along the casing 4, of one of the feet 13, the stem 15 and its prolongation 15^c being perforated laterally, at 15^d, and longitudinally, at 100 15^e, for the passage of air from the channel 11^c, to the boring 13^c, and thence, by the opening 13^c, into the casing 4, and, between the rotor 3^a, and stator 3^b, of the electric 105 motor 3, and out, by the opening 4^c, into the room, or surrounding space.

Figure 5 shews an arrangement of air 110 passages suitable in cases where the rails 11, carrying the spinning-boxes and their adjuncts, are reciprocated as well as rotated, the rails carrying tubes 28, sliding in the tubular part of a bracket-piece 27 secured to a hollow supporting bar 26. The air is passed, or drawn, into the interior 26^a of the 115 bar 26, and passes, by the openings 26^b, into the space 27^a in the part 27, and thence, by the openings 28^a and 28^b in the tube 28, to the passage 11^b, and channel 11^c, in the rail 11, and thence, by the opening 15^d, in the 120 stem 15, to and through the motor as described with regard to the arrangement shewn in the other figures. In both arrangements the course of the air is indicated by arrows.

What I claim is:

1. In electrically driven apparatus, a vertical spindle, an electric motor for driving the same, a housing for said motor, post supports for the housing, and means for 130

ventilating said housing through certain of said post supports.

2. In electrically driven apparatus, a vertical spindle, an electric motor for driving the same, a housing for said motor, post supports for the housing, a channelled base upon which said posts rest, certain of said posts affording passage therethrough connecting the channel in the base with said housing, and means for ventilating the housing through said channel base and connecting passage.

3. In electrically driven apparatus, a base, upstanding posts thereon, a motor, a housing therefor resiliently supported on said posts, and means for ventilating said housing through certain of said supporting posts.

4. In electrically driven apparatus, a base, upstanding posts thereon, a motor, a housing therefor resiliently supported on said posts and having telescopic connection therewith, and means for ventilating said housing through certain of said supporting posts.

5. In electrically driven apparatus, a blast conduit, a motor supporting base associated with said conduit and channelled to communicate therewith, a motor housing supported on said base, and means for ventilating said housing through said base and support.

6. In electrically driven apparatus, a blast conduit, a motor supporting base associated with said conduit and channelled to communicate therewith, a motor housing resiliently supported on said base, and means for ventilating said housing through said base and support.

7. In electrically driven apparatus, a channel base, tubular posts adjustably engaged therewith and communicating with a channel in the base, a motor casing mounted on said posts, and means for establishing a ventilating connection with said housing through said posts and base.

8. In motor driven apparatus, a fixed base having an air passageway therein, a bearing supported on said base, a vertical spindle mounted in said bearing, a motor element carried by said spindle, a motor housing on said bearing, the stator of the motor being carried by said housing, one of said sup-

ports for the bearing being hollow and communicating with the interior of the motor casing on the one hand, and with the passageway in the base on the other hand, to permit the introduction of a cooling blast to the motor chamber.

9. In motor driven apparatus, a fixed base having a passageway therein, supporting posts thereon, one of said posts being hollow, a bearing resiliently supported on said posts, a motor housing associated with said bearing and communicating through said hollow post with the passageway in the base to admit a cooling blast to the motor chamber, in combination with a vertical spindle mounted on said bearing plate and passing through the motor chamber, the rotor of the motor engaging said spindle.

10. In motor driven apparatus, a stationary base having a passageway therein, a bearing resiliently supported thereon, one of said supports being hollow and communicating with the passageway in the base, a motor chamber associated with said bearing and lying above the same and communicating with said hollow support to admit a cooling blast to the motor chamber, a vertical spindle supported in said bearing member below the motor and passing through the motor chamber, together with a steady bearing therefor carried by the motor casing above the motor chamber, substantially as described.

11. In motor driven apparatus, a fixed base having a passageway therein, a hollow rail supporting the same and communicating with said passageway in the base, a bearing supported on said base, said support comprising a hollow post, a motor casing associated with said bearing and having a motor chamber opening to said hollow post to admit a cooling blast to said motor chamber, in combination with a vertical spindle supported in said bearing and passing through the motor chamber.

In testimony whereof I have signed my name to this specification in the presence of two subscribing witnesses.

JAMES CLAYTON.
